UNITED STATES PATENT OFFICE.

GEORGE ARRAS AND DWIGHT E. WORRELL, OF CHICAGO, ILLINOIS.

METHOD OF MAKING LAMP SOCKETS.

Application filed December 31, 1920. Serial No. 434,207.

To all whom it may concern:

Be it known that we, GEORGE ARRAS and DWIGHT E. WORRELL, citizens of the United States, residing at Chicago; in the county of Cook and State of Illinois, have invented certain new and useful Improvements in Methods of Making Lamp Sockets, of which the following is a specification.

This invention relates to the method of making a moulded lamp socket composed of a plurality of parts, and among the objects of the invention are: to make a moulded lamp socket of a plurality of parts in which the lamp terminals are easily accessible; to make a lamp socket in which the parts are easily separated; to provide means for inserting conductors at the time the parts are moulded; to mould the various parts of the socket at the same time; to use a minimum number of dies in moulding the socket parts; and in general, to produce the socket herein shown and described.

In the accompanying drawings, Fig. 1 is a sectional view illustrating the method and apparatus for making a socket of this kind; Fig. 2 is a top view of one of the die parts; Fig. 3 is a view of the die for forming the outside of the principal socket member; Fig. 4 is a view of the die for making the inside of the socket member; Fig. 5 is a side elevation of the completely formed socket; Fig. 6 is a view of the underside of the socket cap taken on the line 6—6 of Fig. 5; Fig. 7 is a sectional view taken on the line 7—7 of Fig. 6 of a completed socket and cap; Fig. 8 is a top view of the socket member taken on the line 8—8 of Fig. 7; Fig. 9 is an enlarged sectional view showing the knockout thread forming parts; and Fig. 10 illustrates a modified form of the cap.

Moulded sockets of porcelain or other insulating materials are well known and commonly used, and the present invention relates to any insulating compound which can be moulded when subjected to heat and pressure or either of them, the present socket being formed of a substance somewhat similar in appearance to hard rubber and purchasable in powdered form ready for use.

This lamp socket as illustrated by Figs. 5, 6 and 7, comprises a socket member 1, having a hollowed out portion 2 into which the contact extremity of an electric lamp is inserted, and having a cap 3 which covers and protects the terminal connections for the socket and is attached to the socket member

by means of a fastening device such as a screw 4 inserted from the interior of the socket into the cap.

In one side of the socket recess is a strip 5 of crimped metal forming threads for the engagement of a lamp socket, and extending through the top of the socket member into a bent extremity 6 of this strip is a contact screw 7. At spaced distances around the inside of the socket recess are strips of thread portions 8 formed up out of the material of the socket itself so that they together with the strip 5 form the engaging and holding and contact means for a lamp socket inserted in the socket member. The central contact screw 4 forms the central terminal for a lamp inserted in the socket member so that both connections are made for a lamp.

In the cap 3, as clearly shown in Figs. 6 and 7, there is a transverse partition 9 which normally separates the ordinary opposite apertures 10 in the edge of the cap, and at the center of the partition is an enlargement 11 in which is imbedded one extremity of a conductor 12 into which the fastening screw 4 is inserted. This conductor strip extends from the central partition into the side wall of the cap, and beneath the conductor is an abutment 13 to assist in holding the conductor in place. Between the partition enlargement 11 and the side wall of the cap 3, a contact screw 14 is inserted into the conductor 12 and forms a binding post for one of the conductors of the lamp.

In practice, a conductor 15 is connected to the contact screw 7 at the top of the socket member before the cap is placed in position and another conductor 16 is connected by the binding screw 14 to the contact piece 12 of the cap. This conductor 16 extends through the opening 10 on its side of the partition 9, and the other conductor 15 extends through the other cap opening 10 on the other side of the partition 9. Thus the lamp terminal connections are separated by the partition 9, greatly lessening the danger for a short circuit between them. In order to assemble the parts after the cap is in position, it is only necessary to insert the screw 4 from the inside of the socket member into the contact member 12 of the cap through the enlargement 11 of the partition 9.

The socket member is preferably made with lateral projections 17 at its upper edge, as shown in Fig. 8, and these projections are intended both to properly position the cap

- by entering the opposite notches 10 thereof, and also to partially fill the opening made thereby, making the conductors fit more closely in the notches. Opposite projections 18 are commonly formed on a shoulder 19 at the outside of the socket member for positioning the socket member in a cover plate with which a socket of this kind is commonly used.
- 10 If desired, the cap 3 may be formed with thin knockout portions 20 opposite the notches 10, so that a pair of notches 10 will be provided on each side of the partition, as shown more clearly in Fig. 10. This will 15 permit the cap and socket member to be connected to conductors running through the cap and not to the conductor terminals as shown in Fig. 7.
- In order to form a two part conductor of 20 this type it is customary to employ an upper and a lower die member for each part. The present invention contemplates the use of one die member for the outer part of one piece and for the inner part of the other 25 piece. This might be continued in the same way, the result being only one more die part than the number of pieces to be moulded will be required. The advantage of this is that the pieces thus moulded will be more uniform 30 and of the same diameter and consistency. In carrying out this invention, a three part mould is employed as conventionally shown in Fig. 1, in which the die parts 21, 22 and 23 are shown in a guide or 35 container 24 receiving pressure from a presser foot 25. At the outside of the guide 24 is a shell 26 surrounding which are electric heating coils 27 and a cooling coil 28.
- The socket member 1 is formed between 40 the die parts 22 and 23 and the cap member is formed between the die parts 21 and 22, the dies being formed with the proper recesses and projections to form the various features of the socket parts which is well 45 known in practice, and will not be specifically enumerated. However, in moulding the contact pieces 12 and strip 5 within the cap and socket members respectively, and in forming the thread portions within the 50 socket member, a somewhat different construction is employed. In the central die member 22 is a bore 28' extending between the upper and lower die pieces and into this bore a removable piece 29 is inserted which 55 has a reduced stem 30 at its lower end for forming the opening in the top of the socket member 1 which receives the screw 4. At the other end of the piece 29 is a shoulder 31 which forms the outer face of the central 60 partition 11 in the cap, and then a reduced portion 32 which forms an unthreaded opening in the partition 11 for the free insertion of screw 4 after cap is formed, and at the 65 end a reduced stem 33 over which the threaded conductor piece 12 is inserted, the stem extending beyond the contact piece into the material of the cap to afford a space 70 therein for the insertion of the screw 4, as shown in Fig. 7. In order that the threads for receiving the screw 14 of the contact piece 12 may not be filled with the moulded insulating material of the cap, the screw 14 is threaded through the piece and placed in position on top of the die 22 when the die is being set for the moulding operation, as 75 shown more clearly in Fig. 2, the head of the screw being inserted in an opening provided for it in the top of the die 22.
- It is customary to cast a designating mark 80 in the edge of the socket member, to indicate the origin thereof, or to designate the capacity for service of the socket member. Such indication, however, would be defaced if it were necessary to remove the socket member 1 from the die by unscrewing it 85 therefrom as will be evident from Fig. 4, as the indicating characters 34 are formed in the face of the die 23. The thread forming portions of the die are therefore made removable, as shown more clearly in Figs. 4 90 and 9, with the exception of course, of the contact strip 5 which is moulded into the material of the socket. The crimped thread strip 5 is held in place on the lower die member 23 by means of a projection 35 which 95 extends through the threaded opening in the bent portion 6 of this strip, the crimped portion being seated in a shallow recess 36 in the side of the die. The other thread portions 8 in each socket member are formed by 100 knockout pieces 37 which are each seated in a side recess 38 of the lower die member 23, and each thread forming piece 37 has a reduced projection 39 which extends through a 105 corresponding opening 40 in the die member 23. The outer face of each knockout piece 37 has a wavy outline 41 to form a corresponding thread portion in the inside wall of the socket member 1 which projects at least the depth of the thread from the inside 110 face of the socket member. This makes the thread portion stand out on the inside of the socket member, and of course, the different thread portions must present the proper portion of the thread to engage a socket there- 115 in.
- When the socket member 1 is completely formed in the die it is desired to remove the socket from the lower die member 23, it is 120 obvious that the socket member cannot be turned or threaded off of the die member 23 without defacing the letters formed by the characters 34. The knockout pieces 37 are therefore provided which may be pressed outwardly and upwardly from the die member 23 carrying with them the formed socket member, and after the extensions 39 slip out of the sockets or recesses 40 therefor, the knockout pieces can be removed or separated 125 from the formed socket member, leaving 130

the threaded portions 8 undamaged, and carrying the crimped conductor strip 5 with the socket in which it is moulded.

In carrying out this invention, a measured quantity of the material of which the socket parts are made is placed between the die members as they are assembled. Heat or pressure, or both, is applied to form the socket parts after which the dies and socket parts may be tempered or cooled by means of a coil 28. The dies are separated and the socket parts are removed therefrom as described. It is obvious that although the dies for a single socket only is shown the same general method may be employed in making any number of sockets at the same time. After the socket parts are formed it is necessary only to insert the contact screw 7 through the top of the socket member 1 and 20 into the contact strip 5 to connect a conductor thereto, and to connect a conductor by means of the contact screw 14 to the conductor 12. The cap is attached to the socket member by means of a screw 4 and the entire socket is then in condition to receive an electric lamp. In order to separate the socket parts, it is necessary only to remove the lamp and the screw 4, whereupon both of the circuit terminals of the socket parts are 30 freely accessible.

We claim:

1. The method of making a multi-part moulded socket between co-operating die members for forming the socket parts at the same time, there being one more die member than the number of socket parts, which consists in introducing between the die members a measured quantity of insulating material which hardens when subject to heat and pressure, and in moulding into each of the socket parts thus formed a conductor which becomes a part of the socket thus formed.

2. The method of making a two part socket by means of an upper, lower and an intermediate die member, which consists in introducing between the intermediate and each of the other die members a measured quantity of insulating material, 50 in supporting an electrical conductor by means of the die which becomes moulded into the material of the socket, and is removed therewith, and in applying heat and pressure to form the socket parts.

3. The method of moulding a two part socket, with upper, lower and intermediate die members of substantially the same external size, which consists in introducing a measured quantity of insulating material 60 between adjacent dies, in inserting the die

members within a guide sleeve, in applying pressure to the die members in the sleeve, in inserting the sleeve and die members within a heating shell, and in cooling the shell after a predetermined heat and pressure has been applied to the material between the dies.

4. The method of moulding lamp socket parts, dies for forming the parts which consists in one of the dies holding an electrical conductor, and seating the head of a screw threaded through the electrical conductor, so that as the insulating material is moulded about the conductor, the conductor becomes embedded in the socket part and the head 70 of the screw which is threaded into the conductor projects from the face of the contact, and the threaded portion of the screw prevents the insulating material from filling the threads in the electrical conductor. 75

5. The method of moulding a socket part with threaded portion therein which consists in providing one of the die parts with removable thread forming portions which are removable with the socket when it is 80 formed so that the threads are not broken in separating the socket from the die, and in then separating the thread forming parts and re-inserting them in the die before the next socket part is formed. 85

6. The method of moulding a socket part having threaded portions therein and indicating characters in one face at right angles to the threads, which consists in providing one of the die parts with thread forming 90 pieces, and in removing the formed socket part and the said pieces together from the die part directly away from the characters formed therein, so that the characters will not be distorted or broken, and in thereafter 100 loosening the thread forming pieces from the formed socket so that the thread portions are not broken thereby.

7. The method of moulding a lamp socket in a die with removable thread forming portions, which consists in applying to this die a crimped conductor strip which is seated in the recess in the die part so that the crimped portion forms projecting threads in the socket member, in moulding the insulation about the conductor member, in separating the part thus formed from the die by removing with it the thread forming pieces and the crimped conductor piece from the die and in loosening the thread forming pieces from the socket member 110 after it is removed thereby. 115
